United States Patent Office.

E. C. MOORE, OF YONKERS, NEW YORK, ASSIGNOR TO TIFFANY AND COMPANY, OF NEW YORK CITY.

Design No. 3,588, dated July 27, 1869.

DESIGN FOR A FORK OR SPOON-HANDLE.

The Schedule referred to in these Letters Patent and making part of the same

To all whom it may concern:

Be it known that I, E. C. MOORE, of Yonkers, in the county of Westchester, and State of New York, have invented or produced a new and original Design for the Handles of Forks, Spoons, &c.; and I do hereby declare the following to be a full, clear, and exact description of the same, reference being had to the annexed photographic views, in which—

Figure 1 represents the design upon the surface of a spoon-handle, and

Figure 2 shows the design formed upon the back of the handle.

The design of the ornamental ribs or beads formed upon the upper surface of the handle, as shown in fig. 1, consists in a pair of scroll-ornaments at *a*, the same being a convoluted continuation of the bead running along the edge of the handle.

At *b* a double-leaved ornament is formed, and at *c* the ribs that run along the small portion of the handle are curved around and united.

At the end of the handle is the shell-ornament *d*.

At the back of the handle a broad shallow groove is formed near the edges, and this is convoluted into the double scroll at *e*.

The petaline ornament at *f* projects along the middle of the handle from the scrolls *e*.

Double-leaf ornaments *g* are applied near the junction of the handle and bowl, or other corresponding part in a fork or similar article.

What I claim, and desire to secure by Letters Patent, is—

The design of the ornamental configuration for a handle, substantially as described and represented.

In witness whereof, I have hereto set my signature, this 30th day of June, A. D. 1869.

E. C. MOORE.

Witnesses:

FREDERIC VOSS,
A. B. GODFREY.
